UNITED STATES PATENT OFFICE.

WILLIAM H. SMITH, OF BRIDGEPORT, CONNECTICUT.

SPRING WHEEL.

Application filed February 27, 1922. Serial No. 539,674.

To all whom it may concern:

Be it known that I, WILLIAM H. SMITH, a citizen of the United States of America, residing at Bridgeport, in the county of 5 Fairfield and State of Connecticut, have invented certain new and useful Improvements in Spring Wheels, of which the following is a specification.

This invention relates to certain new and 10 useful improvements in spring wheels, and has particular reference to the provision of an improved form of spring wheel embodying a series of spaced concentric bands held resiliently in their proper normal relation by means of circular spring elements.

The primary object of the invention is to 15 provide a spring wheel of the above type wherein the construction embodies a combination of simplicity and durability as well 20 as efficient operation, and meets the requirements for a successful commercial use.

Another object in the invention is to provide the circular spring elements in disconnected spaced relation for each circular 25 series thereof whereby extreme resiliency may be obtained, the spring elements acting as connecting means for a plurality of concentric resilient bands whose resiliency combines with the resiliency of the spring elements 30 for efficient operation.

With the above general objects in view the invention consists of the novel combination and arrangement of parts hereinafter 35 more fully described in connection with accompanying drawings, and in which like reference characters designate corresponding parts throughout the several views.

In the drawings:

Figure 1 is a fragmentary side elevational 40 view of a vehicle wheel constructed in accordance with the present invention.

Figure 2 is a sectional view taken substantially upon line II-II of Figure 1, and

Figure 3 is a perspective view drawn on a 45 larger scale illustrating cushion members interposed between the spring elements as indicated in Figure 1.

Referring more in detail to the several 50 views, the present invention includes three or more concentric annular bands, five of the same being herein shown as the preferred construction and respectively indicated by the numerals 5, 6, 7, 8 and 9. These bands are all constructed of resilient sheet metal,

and as shown, they preferably are gradually reduced in distance in which they are spaced apart inwardly so that the series of spring elements gradually also decrease in size, the smallest spring elements being 60 interposed between the two innermost bands and the largest spring elements being interposed between the outermost bands. The spring elements consist in circular sheet metal spring members, those of the outermost series being denoted by the numeral 10 and shown as riveted or secured in an equivalent manner as at 11 at their inner portions to the band 8 and similarly secured at their outer portions as at 12 to the band 9, the spring elements of this series being 65 in spaced relation so that flattening of said elements may take place when the rims are flexed or displaced under load.

The next series of spring elements is denoted by the numeral 13, the same having their inner portions riveted as at 14 to the band 7 and their outer portions riveted as at 15 to the band 8, the spring elements of this second series of spring elements being 70 also in spaced relation at the adjacent sides of the same so as to permit flattening or flexing of the same as above mentioned with respect to the spring elements 10. In a like manner the spring elements 16 of the next 75 circular series are attached to the bands 6 and 7 and the innermost series of elements 17 are attached in a like manner to the bands 5 and 6.

It will be noted that the spring elements 80 of one series are in staggered relation to those of the series of elements at either side thereof so that the bands may easily flex between the spring elements of adjacent series whereby the strains are distributed over the entire wheel for insuring durability and long life to the wheel.

As shown, the spring elements may gradually decrease in width and this is also true of the band, the outermost band 9 being 85 the widest the bands gradually decreasing in width until the innermost band 5 is of the smallest width as shown in Figure 2. The outermost band 9 may be formed in any suitable manner for reception of a resilient 90 tread 18, preferably of rubber or rubber composition, and all of the bands will be 95 flexible with the exception of the band 5 which constitutes the periphery of a hub member including also side plates or disks 100 105 110

19 and 20, the disk 20 being employed also to furnish the usual brake drum 21 by flanging said disk 20 in the usual manner, the parts being held together by bolts as at 5 20' as is well known in the vehicle wheel art.

For extreme economy in manufacture, the spring elements and the bands may be formed of thin gage metal and in order that the same will not have too high resiliency, 10 rubber or other cushion members or blocks 22 may be interposed between the side portions of the adjacent spring elements of each series as denoted in Figure 1. While these cushion blocks may be attached or otherwise 15 secured in place, they will probably remain in place under ordinary conditions of use by simply fitting the same tightly between the adjacent spring elements and forming the blocks with arcuate side faces conforming 20 the shape of the spring elements. The arcuate curvatures of the side faces of the blocks 22 will of course be concave and the outer portions of the blocks may be made slightly larger than the inner portions of the 25 same as shown, if found desirable. While these blocks are compressible they will resist the flexing of the spring elements to a great extent and compensate for the use of extremely thin and highly resilient rims and 30 spring elements.

The object of making the outer bands and the outermost series of spring elements of greater width is to provide a broad traction surface and greater strength at the remote 35 points from the hub, which portion of the wheel will of course be subjected to the most severe lateral strains and the like when the wheel is in use.

From the foregoing description it is believed 40 that the construction and operation as well as the advantages of the present invention will be readily understood and appreciated by those skilled in the art.

Minor changes may be made without departing 45 from the spirit and scope of the invention as hereinafter claimed.

Having thus described the invention, what I claim is:—

1. A spring wheel comprising a hub member including an inner band forming a portion of the hub, a plurality of resilient circular concentric bands of sheet metal disposed about said hub band and a plurality of spring elements disposed between adjacent ones of said bands, each of said elements comprising a ring of resilient sheet metal, the spring elements of each series being in side by side spaced relation and said elements being unconnected with each other and attached only at their inner and outermost points to the bands, the series of spring elements between adjacent bands being in staggered relation to those of the series at either side thereof, said bands being spaced gradually lesser distances apart 55 inwardly, and said spring elements of the series of spring elements gradually decreasing in size inwardly, and cushion blocks having concave side faces conforming to the spring elements and interposed between said elements for resisting flexing of the latter.

2. In a spring wheel wherein a plurality of resilient bands are normally maintained circular and concentric by means of a plurality of circular series of spring elements 75 which are disposed between adjacent ones of said bands in radially staggered relation, and wherein the spring elements between the bands are gradually spaced at lesser distances apart inwardly with the spring elements of the several series of spring elements 80 gradually decreasing in size inwardly, the bands and spring elements formed of continuous pieces of sheet metal of single thickness with the spring elements of the several series arranged with their peripheries adjacent, but in spaced relation, and unconnected with each other and attached only at their inner and outermost points to the 85 bands.

In testimony whereof I affix my signature.

WILLIAM H. SMITH.
